UNITED STATES PATENT OFFICE

MICHAEL G. BOOSALIS, OF ROCHESTER, AND ALEXANDER S. T. LAGAARD, OF MINNEAPOLIS, MINNESOTA, ASSIGNEES, BY DIRECT AND MESNE ASSIGNMENTS, OF ONE-HALF TO SAID BOOSALIS AND ONE-HALF TO GEORGE J. MITCHELL, OF MINNEAPOLIS, MINNESOTA

DISPLAY DEVICE

Application filed September 10, 1928. Serial No. 305,012.

Our invention relates to display devices and has for its object to provide a device including a case with a window therein along which an endless display member may be continuously moved.

Another object of the invention resides in forming said case with an opening and in providing a closure for said opening, said closure supporting said window.

10 A still further object of the invention resides in detachably mounting within said case a reflector having a light source therein, said reflector being removable from said case through said opening.

15 A still further object of the invention resides in attaching a roller to said reflector and in attaching a second roller to said case, said endless member passing between said rollers, and in further providing resilient means for holding said rollers in contact with said endless display member.

20 A feature of the invention resides in providing a motor and reduction gearing operated thereby, said gearing being arranged to drive one of said rollers to move the display member along said window, said gearing permitting the moving of said reflector, display member and one of said rollers through said opening for the purpose of changing display members.

25 Another feature of the invention resides in providing a U-shaped support to said motor and reduction gearing, said support being attached to said case and carrying said second roller.

30 With the foregoing and other objects in view which will appear in the following description, the invention resides in the novel combination and arrangement of parts and in the details of construction hereinafter described and claimed.

In the drawings:

Fig. 1 is a front elevational view of a display device illustrating an embodiment of our invention.

Fig. 2 is a sectional view taken on line 2—2 of Fig. 1.

Fig. 3 is a vertical sectional view taken on line 3—3 of Fig. 2.

Fig. 4 is a fragmentary sectional view of

the reduction gearing taken on line 4—4 of Fig. 3 and drawn to an enlarged scale.

Fig. 5 is a sectional view taken on line 5—5 of Fig. 4.

Fig. 6 is a fragmentary detailed view of a portion of the supporting frame work illustrating the method of attaching the reflector thereto.

Our invention is enclosed within a case A which comprises a back 10, sides 11 and 12, 60 a bottom 13 and a top 14. This case is opened at the front as indicated at 17 except for cross pieces 15 and 16. The opening 17 is adapted to be closed by means of a closure 18 which is constructed with a window 19 occupying a 65 prominent portion of the same. The closure 18 is preferably hinged to the side wall 11, case A, by means of hinges 20 so that the same may be swung outwardly from the case to give access to the interior thereof through 70 the opening 17. If desired, a lock and key of ordinary construction may be employed to hold the closure 18 in closed position, or any other suitable fastening device may be utilized.

75 Within the interior of the case A is mounted a support which comprises a U-shaped frame member 21 having longitudinal portions 22 and 23 connected by a transverse portion 24. This frame member is disposed near the upper portion of the case and the frame portions 22 and 23 are preferably recessed in the side walls 11 and 12. At the forward edges of the walls 11 and 12 are arranged vertical frame members 25 and 26 which are attached to the frame member 21 by means of screws 27. These frame members are constructed with bayonet slots 28 as shown in detail in Fig. 6 which serve to support the reflector and guiding means for the display proper. 80 85 90

Within the case A is disposed a reflector 29 which is constructed with parallel side walls 30 and 31 connected by sloping rear walls 32 and 33 and a back 34. This reflector is formed with an opening at the front which 95 is adapted to be closed by a pane of glass 132 supported in U-shaped guides 33 attached to the side walls 30 and 31 of said reflector. At the upper ends of these walls are attached small castings 34 by means of screws 35, 100

which castings are formed with pins 36 extended outwardly therefrom. The pins 36 are so disposed as to be received in the bayonet slots 38 and serve to hold the entire 5 reflector detachably mounted within the case proper. It will be noted from Fig. 3 that the reflector 29 is disposed slightly inwardly from the window 19, the glass 132 being arranged parallel therewith. Within the 10 interior of reflector 29 is disposed a light socket 37 adapted to receive a light bulb 38. This socket is mounted upon a bracket 39 which is attached to the back 34 of said reflector and may be wired by means of a flexible conductor 40 not shown in detail in this application.

The display member proper consists of an endless belt 40 of suitable transparent material such as certain grades of paper, cloth, celluloid or the like. This belt is of an appreciable length and is adapted to extend between the glass 32 and window 19 and over and above the reflector 29 and into the space 41 within case A below said reflector. At the 20 upper and lower portion of the front of reflector 29 are arranged rollers 42 and 43 which are journaled in the castings 34 and which serve to guide the display member 40 so as to cause the same to move in spaced relation to the glass 132 and the inclined wall 132. In addition to these rollers, I employ 30 another roller 44 which has rigidly attached to it a shaft 45. This shaft is journaled in two bearings 46 attached to the side walls 30 and 31 of reflector 29 and is positioned immediately to the rear of back 34.

The roller 44 serves to drive the endless display member 40 in the following manner. For the purpose of providing a frictional drive between the roller 44 and display member 40, an idler roller 47 is utilized which is journaled in a swinging frame 48. This frame terminates in inwardly turned trunnions which are journaled in clips 50 attached to the portion 24 of frame 21. A tension coil spring attached at one end to the swinging frame 48 and at its other end to the frame portion 23 serves to hold the roller 47 in contact with roller 44. This provides a friction drive between the roller 44 and the 50 endless display member 40 so that when the said roller is rotated, said member is caused to move continuously along the window 19. In order to provide a display member of suitable length, the same is folded successively in loose folds as indicated at 52 in Fig. 3 in the space 41 of case A below the reflector 29. As the display is fed, the portion 53 thereof passes along the window 19 and is drawn from the bottom of the pile while the portion 54 thereof is gradually piled on top of the pile. In this manner the feeding of the display member is continuous and the length of the same is dependent only upon the available space in which the folded member is 65 disposed.

For the purpose of operating roller 44, I employ a motor 55 and a train of reduction gearing shown in detail in Figs. 4 and 5. Motor 55 may be of any suitable type and is attached to a block 56 mounted on the portion 24 of frame member 21. Adjacent to said motor is disposed a gear housing 57 which is formed with ears 58 by means of which the same is attached to said frame portion 24 by bolts 59. At the upper portion of this gear housing is journaled a shaft 60 which has cut in it a spur pinion 61. This pinion meshes with a spur gear 62 journaled on a screw 63 which is attached to a boss 64 formed in housing 57. A spur pinion 65 is rigidly secured to the gear 62 and meshes with a second spur gear 66. This spur gear has attached to it a spur pinion 67 which is journaled on a screw 68 similar to the screw 63 and which is secured to the case in the same manner. Pinion 67 meshes with a third spur gear 69 which, similar to the others, has attached to it a spur pinion 70 and is journaled on a screw 71. At the lowermost portion of the case are formed two bosses 72 and 73. The boss 72 is bored to form a bearing for a shaft 74 while the boss 73 is threaded to receive a bushing 75 which forms a second bearing for said shaft. This shaft has attached to it a spur gear 76 which meshes with the spur gear 70 on screw 71. Shaft 74 forms the driving means for the roller 44 and as will become evident, is driven from shaft 60 at a greatly reduced speed. As will be noted in Figs. 2 and 3, the shaft 77 of motor 55 is disposed in alignment with shaft 60. For effecting a drive between said motor and shaft, I employ a coil spring 78 which is attached at one end to a collar 79 secured to shaft 77 and at its other end to a collar 80 secured to shaft 60. This coil spring forms a flexible connection between the two shafts and at the same time serves to compensate for any irregularity in the alignment of the two shafts. The protruding end of shaft 45 has attached to it a gear 81. This gear is adapted to mesh with a similar gear 82 attached to the protruding end of shaft 74. These two gears are preferably of a sufficiently large pitch so that enough play may be had between the teeth thereof to permit of sliding the pins 36 upwardly to dislodge the same from the bayonet slots 28.

In the use of the device the door 18 is swung open upon its hinges. The reflector 29 with the various parts attached thereto, is then removed from the case by lifting the same upwardly and out of the bayonet slots 28. The particular display member to be used in the device is then placed over the entire reflector with the upper portion thereof carried by the roll 32 and passing over the roll 34. Reflector 29 with the display member so disposed is reinserted into the case. As the pins 36 enter the bayonet slots 28, the

teeth of the two gears 81 and 82 are brought into mesh and roller 47 through spring 51 is brought into contact with roller 44 bearing against the display member 40 so as to effect a driving connection between said display member and said roll. The machine is then started in operation and the display member guided over the roll 42 until all of the lowermost portions of same have been fed into the space 41 of case A. When this occurs, the closure 18 may be shut and the device will continue to operate incessantly, successively showing various displays upon said display member.

15 The invention is exceedingly simple and effective in operation and will not readily get out of order. An extremely long display may be utilized with a relatively small case so that a sufficient amount of display matter may be displayed. New display members may be quickly and continuously inserted in the machine by simply removing the reflector and associated parts without the necessity of threading the same into the device after the 25 parts are in place. All splicing of the display member may be accomplished outside of the device so that continuity of the display member and smoothness of operation and lack of interruption result. All of the 30 high speed reduction gears are enclosed within a single case which may be readily packed with grease so as to practically require no attention.

Changes in the specific form of our invention as herein disclosed may be made within the scope of what is claimed without departing from the spirit of our invention.

Having described our invention what we claim as new and desire to protect by Letters 40 Patent is:

1. A display device comprising a case, a reflector within said case housing a light source, a roller attached to said reflector, a window formed in said case in front of said reflector, an endless display member movable in front of said window and guided by said roller, and means attached to said case for driving said roller and moving said display member.

50 2. A display device comprising a case having an opening therein, a closure for said opening formed with a window, a reflector removably attached within said case in back of said window, an endless display member adapted to be moved along said window, a roller attached to said reflector for guiding said display member and means within said case for driving said roller, said roller, reflector and display member being removable from said case through said opening.

60 3. A display device comprising a case having an opening therein, a closure for said opening formed with a window, a motor within said case, reduction gearing driven by said motor including a driven pinion, a reflector

disposed within said case having a light source therein, a roller journaled to said case, said roller having a gear adapted to mesh with said pinion, means for removably supporting said reflector within said case, and an endless display member driven by said roller and adapted to pass along said window.

4. A display device comprising a case having an opening therein, an endless display member, guiding means for said display member detachably mounted within said case and adapted to be removed therefrom through said opening, a pair of rollers for driving said display member, resilient means for holding said rollers in frictional contact, one of said rollers being attached to said guiding means and being removable from said case therewith, the other said roller being attached to said case, and means within said case for operating one of said rollers.

5. A display device comprising a case having a window, an endless display member adapted to be moved along said window, a U-shaped support within said case, a reflector within said case, a roller attached to said reflector, an endless display member adapted to be guided by said roller, a motor attached to said U-shaped support, transmission gearing attached to said U-shaped support and driven by said motor, and means for operating said roller from said transmission gearing.

6. A display device comprising a case having an opening therein, a window in said case, an endless display member adapted to be moved along said window, guiding means for said display member removable from said case through said opening, a pair of rollers for moving said endless display member, one of said rollers being mounted on said guiding means and the other of said rollers being attached to said case, a motor, and means for driving one of said rollers from said motor.

7. A display device comprising a case, a reflector having converging walls disposed near the upper portion of said case and forming an upper and lower compartment within the same, a roller at the converging portion of said reflector, an endless display member adapted to pass around said reflector and to be driven by said roller, a motor and transmission gearing disposed in said upper compartment for operating said roller, said lower compartment serving as reserve space for said display member.

8. A display device comprising a case, a movable display, a supporting structure therefor including a track, a reflector and a light source associated with said track and projecting light rays through said display, operating means carried by said supporting structure for moving said display past said light source, said supporting structure, display and operating device being detachably connected to said case and bodily removable therefrom, driving means carried by said

case, and disconnective means for driving said operated means from said driving means.

9. A display device comprising a case, a movable display, a reflector and a light source within the same, a track positioned in front of said light source for guiding said display past said light source, a roller mounted on said reflector for moving said display, means for detachably mounting said track and reflector with respect to said case, driving means within said case engaging said roller and driven from said driving means.

10. A display comprising a case, an endless display, means for detachably supporting said display relative to said case and including a window, driving means carried by the case, disconnective means for driving said case from said driving means, and disconnective means for tensioning said display at said window.

20. In testimony whereof, we have affixed our signatures to this specification.
